UNITED STATES PATENT OFFICE

RUSSELL C. GROSS, OF PHILADELPHIA, PENNSYLVANIA, ASSIGNOR TO SOLIDON PRODUCTS INC., OF PHILADELPHIA, PENNSYLVANIA, A CORPORATION OF DELAWARE

CORNER STRIP

Application filed April 13, 1928. Serial No. 269,810.

My invention relates to a reinforcing device for wall and ceiling construction and the method of using the same, and particularly to the application of wall board, insulation board and such, to building frames independently of nailing headers disposed between adjacent framing timbers.

There are many types of composition wall boards, insulation board and such, including 10 gypsum board, on the market, and the term "wall board" as herein used is understood to include all types of wall covering to which the several features of the invention are applicable. Such wall board is usually manufactured in lengths to extend from the floor to the ceiling and is generally of a width which is a multiple of the spacing between the framing timbers of the building, which is usually 16 inches.

20 Each sheet of wall board must be nailed along each edge and along any framing timbers across which such sheet extends. When wall board is used as a side wall of a building the specifications as to nailing can be followed without the addition of any extra framing, as the studs extend along the edges of the sheets and the plates of the building frame extend across the top and bottom edges, thereby providing nailing support for the 30 sheets of wall board around their entire perimeter.

When wall board is applied to a ceiling it is nailed directly to the joists where the joists engage it. At the ceiling angle, formed 35 at the intersection of the joists and the plate surmounting the studding defining the side wall of a room, the edge of the wall board that extends parallel to the plate and across the ceiling joists has no timber under it to 40 which it may be nailed. To prevent the wall board from warping along the ceiling angle, and to furnish necessary support for it, nailing headers are placed between the joists above the edge of the wall board. The insertion of nailing headers is expensive by reason of added labor caused in part by their inaccessibility which makes correct fitting and nailing difficult. They are often so insecurely fastened that the subsequent driving 45 into them of the nails holding the wall board

loosens them and forces them out of place. In securing the nailing headers they must be toe-nailed in place.

I provide a reinforcing device for application to a frame structure at the joints between adjacent sheets of building material, either at the ceiling angle or at an intermediate angle of a wall or ceiling. The reinforcing device extends across and is secured to a plurality of the framing timbers at the joint, for 55 supporting the edge of the sheets of wall board without the necessity of providing nailing headers. The application of the reinforcing device to a frame structure is much quicker, requires less labor, fewer nails, and 60 results in a better and stronger joint than is obtainable by the use of nailing headers.

65 At the ceiling angle the reinforcing device is also used to prevent the formation of a crack between the sheets of wall board upon the settling of the building frame, or the shrinking or warping of the frame. The reinforcing device also resists the separation of the various framing timbers by tying them 70 together.

75 The accompanying drawings illustrate certain preferred embodiments of the invention, in which—

Figure 1 is a perspective view of a portion of a building structure illustrating the application of my invention to a ceiling angle;

Figure 2 is a sectional view taken along the section line II—II of Figure 1;

Figure 3 is a view similar to Figure 2 after the separation of the joists and studding;

Figure 4 is a fragmentary perspective view showing the application of my invention to a steep roof;

Figure 5 is a sectional view thereof taken along the section line V—V of Figure 4;

Figure 6 is a sectional view showing the application of my invention to another type of ceiling angle;

Figure 7 is a perspective view of a reinforcing device for application to a ceiling angle; and

Figures 8, 9 and 10 are end views of different shapes of reinforcing devices.

Referring to Figure 1, a portion of a building 100 2 is outlined by framing timbers com-

prising a plurality of joists 4 constituting a ceiling, and a plurality of studs 5 and cooperating plates 6 disposed at the top and bottom of the studs 5 and constituting a side wall.

5 Sheets 7 of wall board are secured by nails 8 to the joists 4, studs 5 and plates 6. A reinforcing device 10 is mounted on one or more of the plates 6 and studs 5 in the included angle between the ceiling and side wall.

10 The reinforcing device 10, in the form of a reinforcing angle shown in detail in Figure 7, is provided with a flange 11, a strengthening and spacing rib 12 and a flange 14 extending substantially parallel to the rib 12 and spaced therefrom a distance substantially equal to the thickness of a sheet of wall board.

15 In applying the reinforcing angle 10 to the framing timbers, the flange 11 is secured by small nails 15 to the plates 6 and a plurality 20 of studs 5, with the flange 14 in engagement with the under surfaces of the joists 4 but free therefrom.

The length of the reinforcing angle 10 may be varied as desired. In general I prefer 25 that its length shall be a multiple of the standard spacing of the joists and other timbers, that is 16 inches, in order that it may act as a tie between a number of the timbers for preventing their separation. After the 30 reinforcing angle 10 is in place, the sheets 7 of wall board are applied to the studs 5 with the rib 12 serving as a spacer against which the upper edges of the sheets 7 abut.

The sheets 7 are secured to the plates 6 by 35 certain of the nails 8 which also extend through the flange 11. The edges of the sheets of wall board 7 applied to the joists 4 are inserted into the space between the rib 12 and the flange 14. The ends of the sheets 7 40 inserted into the reinforcing angle 10 are left free from the joists 4 for a distance from the ceiling angle in order to prevent opening of the joint, as hereinafter described.

By reason of the support given the edges 45 of the sheets of wall board secured to the joists 4 by the rib 12 and flange 14 it is unnecessary to provide nailing headers between the several joists 4. This results in economy of time, labor and material. The reinforcing 50 angle also results in a perfectly true ceiling angle as it prevents warping of the edges of the sheets and does not depend upon nailing headers which are apt to become loosened in service. After the sheets of wall board 7 55 are in place, the joint between them may be filled with filling material 16.

Referring particularly to Figures 2 and 3, upon the occurrence of a separation between the plate 6 and the joists 4 such as may be 60 caused by the settling of the building, the free ends of the wall board adjacent the edge confined between the rib 12 and flange 14 assumes a curved position, thereby keeping the joint at the ceiling angle closed rather than permitting the formation of unsightly open-

ings and cracks. Upon a settling movement, the flange 14 curves to substantially the same extent as do the free ends of the wall board.

Referring to Figures 8, 9 and 10, the rib 70 12 may be spaced different distances from the flange 14 and is given a slope in order to permit its use with wall boards of different thicknesses. For example, the reinforcing angle shown in Figure 8 may have a distance *ac* 75 between the lower surface of the flange 14 and the tip of the rib of 1/2 inch, and the distance *ab* from the base of the rib to the lower surface of the flange 14 of 7/16ths of an inch, in which case the supporting angle is 80 adapted for use in connection with sheets varying from 7/16ths of an inch to 1/2 inch in thickness.

In Figure 9 the distance *ac* is shown as 85 7/16ths of an inch, and the distance *ab* as 3/8ths of an inch; while in Figure 10 the distance *ac* is shown as 4/16ths of an inch and the distance *ab* as 3/16ths of an inch. It is to be understood that the foregoing examples are given by way of illustration and are 90 not to be construed as limiting the invention to any particular thickness of sheets.

In Figures 4 and 5, the invention is shown applied to a sharp roof where the sheets of wall board 7 are supported by rafters 21 that 95 meet to form the ridge of the roof. A reinforcing angle 22 is secured by nails 24 to one set of rafters and extends beneath the sheets of wall board carried between adjacent rafters. The reinforcing and spacing rib is eliminated in this form of the invention as the angular disposition of the sheets of wall board relative to direction of the force of gravity and their abutting relationship prevents sagging along their edges and spaces them while 100 being applied as the end of one sheet engages the outer surface of the complementary sheet.

Referring to Figure 6, for use with ceiling angles formed between rafters 25 and joists 26, I provide a reinforcing angle 27 provided 105 with a spacing rib 28 having a hooked portion 29 that underlies the surface of the sheets of wall board carried by the rafters 25. The wall board carried by the joists 26 is tapered for insertion between the upper surface of 110 the rib 28 and the flange 30 of the reinforcing angle attached to the joists 26. Filling material 29a may be applied to the finished joint, if desired.

The material of the several reinforcing devices shown in Figures 6, 7, 8, 9, and 10 is preferably of relatively light gauge metal through which nails can be readily driven, and which has the desired flexibility to permit functioning, as shown in Figure 3, where 115 bending is desired.

While I have shown and described certain present preferred embodiments of the invention, it is to be understood that it may be otherwise embodied and practiced without 120 130

departing from the spirit or scope of the appended claims.

I claim:

1. A building comprising a plurality of spaced framing timbers, a sheet of wall board carried thereby and spanning a plurality of said timbers, a reinforcing device extending across said timbers having an edge within the lateral projection of said sheet and at least partially enclosing an end of said sheet for supporting it between the timbers.

2. A building comprising a plurality of spaced framing timbers, a sheet of wall board carried thereby and spanning a plurality of said timbers, a metal reinforcing device extending across said timbers having an edge within the lateral projection of said sheet and engaging an end of said sheet for supporting it between the timbers.

3. A building comprising a plurality of spaced framing timbers, a sheet of wall board carried by and spanning the space between a plurality of said timbers, and a reinforcing device having an edge within the lateral projection of said sheet and at least partially enclosing an end of the sheet between said timbers for supporting it.

4. A building comprising a plurality of framing timbers, a sheet of wall board carried by and spanning a plurality of said timbers, and a reinforcing device having an edge within the lateral projection of said sheet and extending across and outside of a plurality of said timbers for engaging and supporting said sheet between said timbers.

5. In a frame structure, a plurality of intersecting frame portions, wall board having overlapping edges applied to adjacent surfaces of the frame portions, an edge of the wall board adjacent to the intersection of the frame portions being left free from its supporting frame portion, and securing means for the free edge of the wall board carried only by another frame portion and insertible between said free edge and its supporting frame portion for maintaining the edges in overlapped relation during relative movement between said frame portions.

6. In a building structure, a plurality of intersecting frame portions, wall board with adjacent edges forming substantially closed joints applied to adjacent surfaces of the frame portions, an edge of the wall board adjacent to the intersection of the frame portions being left free from its supporting frame portion, and supporting means for the free edge of the wall board carried only by the other frame portion and movable with said other portion for flexing the free edge of the wall board and preventing the separation of the wall board during relative movement between the frame portions.

7. In a building, a group of spaced frame members, a second group of spaced frame members intersecting the first named group,

wall board carried by said groups of frame members with overlapping edges adjacent the intersection of said groups of frame members, and a reinforcing device for at least one of the overlapping edges of the wall board, said reinforcing device spanning the frame members of one of said groups and free therefrom and secured to the other group of frame members, whereby upon relative movement between the groups of frame members the edges are maintained in overlapping relation.

8. In the method of applying wall board to an intersecting ceiling and side-wall of a frame structure, the steps consisting in attaching a reinforcing angle to the side-wall near its intersection with the ceiling, securing wall board to the wall and overlying a portion of the reinforcing angle, and securing wall board to the ceiling with an edge in overlapping relation to the wall board carried by said wall and with said edge in engagement with said reinforcing angle and freely movable therewith.

9. A reinforcing member comprising a metal sheet having a substantially flat body portion merging into a laterally extending doubled portion, and a substantially flat portion extending at an angle to the first-named flat portion and co-operating with the doubled portion to form a seat for a sheet of wall board.

In testimony whereof I have hereunto set my hand.
